TRAY FOR CONDIMENT CONTAINERS

Morris Friedman, New York, N.Y., and Andrey V. Mackey, Ambler, Pa., assignors to Minerware, Inc., New York, N.Y., a corporation of New York, and H.M.S. Associates Co., Willow Grove, Pa., a corporation of Pennsylvania

Filed Mar. 26, 1964, Ser. No. 79,211

Term of patent 14 years

(Cl. D44—24)

FIG. 1 is a front elevational view of a tray for condiment containers showing our new design;
FIG. 2 is a top plan view of the tray of FIG. 1;
FIG. 3 is a bottom plan view of the tray of FIG. 1; and
FIG. 4 is a side elevational view of the tray of FIG. 1.

We claim:

The ornamental design for a tray for condiment containers, substantially as shown.
